invention because said portion is to be melted and solidified again so that the two portions may be joined again so that a uniform, solid casting is secured. Hence, these two portions may be joined together by a casting process. After the casting and the new base casting has been hardened, the melted metal is to be melted to form a base casting which is to be joined to the casting of the two portions.

UNITED STATES PATENT OFFICE

2,011,024

ELECTRIC SOCKET

**John Weritz, Cicero, and Daved Hirshfield,
Chicago, Ill.**

Application June 7, 1929, Serial No. 369,040

2 Claims. (Cl. 173—344)

The invention relates to electric light sockets and the socket according to the present invention is especially adapted to be used in connection with narrow reflectors such as are commonly used on reading lamps and the like.

The object of the invention is to provide a socket which consists of two parts hingedly connected with each other so, that the one part may be fastened relatively, stationary and permanently inside the reflector while the other portion which really contains the socket proper, may be pivoted outwardly so, that it will be easy to insert or exchange an electric light in said socket.

A further object of the invention is to provide electric contacts in the two parts of the socket, which will cooperate with each other in such a manner, that the circuit energizing the electric light will be closed, when the part containing the socket proper is in working position, that is, when it is located inside the reflector.

A still further object of the invention is to provide a socket for electric lamps consisting of two parts hingedly connected with each other and having means for urging said two parts out of working position after the electric contacts, with which the two parts are provided and which cooperate to close the circuit in which the socket is arranged, have been disengaged from each other.

Other objects of the invention not specifically mentioned will be easily ascertained and understood from the following description in connection with the accompanying drawing forming a part thereof. It is however to be understood, that the invention is not to be limited or restricted to the exact formation and construction shown in the drawing and described in the specification, but that said invention is only to be limited by the scope of the claims appended hereto.

In the drawing illustrating a preferred embodiment of the invention:

Fig. 1 is a side view of a socket according to the present invention, the two parts being shown in a position, in which the contacts electrically connecting said two parts with each other are closed.

Fig. 2 is an end view of Fig. 1 and

Fig. 3 is a sectional view taken on line 3—3 in Fig. 2, the two parts of the socket being shown in a position, in which the contacts electrically connecting said two parts are open.

Fig. 4 and Fig. 5 are end view and top view respectively of a preferred form of a binding post used in connection with the socket, according to the present invention.

The socket according to the present invention has a body consisting of a main portion 6, in which

therein is a base casting which is to be melted and solidified again so that the two portions may be joined together by a casting process. After the casting and the new base casting has been hardened, the melted metal is to be melted to form a base casting which is to be joined to the casting of the two portions.

Application June 7, 1929, Serial No. 369,040

2 Claims. (Cl. 173—344)

the socket proper is arranged. In the drawing a common screw socket is shown consisting of a metal sleeve 1 having threads formed in its inner circumference. This metal wall is electrically connected with a contact plate 8, the connection being made in any suitable way as shown at 7a in Fig. 2. On the bottom of the socket a spring contact 9 is provided, which in turn is electrically connected with a contact plate 10 as shown in Fig. 3. In the main portion 6 a second portion 11 is pivotally attached by means of a hinge 12. This portion 11 is adapted to be fastened in any desired manner relatively, stationary and permanently to any desired supports. On the free end of said second portion 11 a pair of contact rods 13 of any suitable construction is provided and they are so arranged that each of said rods will contact with one of the plates 8 and 10 respectively, when the two socket portions 6 and 11 are in the position shown in Fig. 1. From the foregoing it will be apparent that the rods 13 function as detent members and maintain the member 11 in operative position with the member 6.

Preferably the end of the rods 13 extending somewhat beyond the portion 11 has a globular shape and the free ends of the plates 8 and 10 are formed with respective hollows 13a so as to accommodate said globular parts of the contact rods. When the two portions 6 and 11 are forced against each other the globular ends of the contact rods 13 will be forced into the hollows formed in the contact plates, so that the two contact portions will be held in working position through the engagement of the contact rods and contact plates. The plates 8 and 10 are resilient, readily permitting a flexing thereof, whereby the rods 13 may seat in the hollows.

A pair of binding posts 14 is provided in the second socket portion 11 and electrically connected with the contact rods 13.

The exact construction of the binding post shown in Figs. 4 and 5 and indicated in the other figures of the drawing is the subject matter of Patent #1,795,627 issued March 10, 1931 and said binding posts are therefore not described in detail in this application. It is hereto to be noted, that binding post of any suitable construction may be used in connection with the present invention as long as they are adapted to be connected to and to hold electric wires or cables 15 and to be electrically connected with a plate 14 fastened to the second socket portion 11 and contacting with the spring contact 13, so that an electric lamp, inserted in the socket 1, may be

energized when the contact rods and contact plates are in working position.

By the use of a socket as described above the exchange of an electric lamp arranged in said socket will be facilitated in so far, as it is not necessary to disengage such lamp while it is arranged in the narrow confined space inside of a lamp reflector, but that it is possible to pivot the portion of the body containing the electric lamp into a position where said lamp extends outwardly of a reflector in which the lamp is being used. At the same time the connection between the electric circuit and the lamp is automatically broken when the lamp is pivoted into position for removal, so that it will be impossible to receive an electric shock while removing or exchanging a lamp.

Having described our invention and how the same is to be performed we claim as new and desire to secure by Letters Patent:

1. In a device of the class described a body portion, a socket for an electric lamp, a pair of contact plates, one of which is connected with said socket, a spring contact electrically connected with the second plate and arranged at

the bottom of the socket but spaced therefrom, a second body portion, a hinge connecting said two body portions with each other, a pair of binding posts in said second body portion, a pair of contact rods electrically connected with said binding posts, the outer ends of said rods being of globular shape and the outer ends of said contact plates forming sockets adapted to engage said globular ends.

2. In an electric fixture, a body member having a socket including a pair of contact plates, one of which is connected with the socket and the other of which includes a spring contact within the socket, each of the contact plates terminating exteriorly of the socket, a second body member hingedly connected with the first body member, a pair of binding posts in the second body member, a contact rod electrically connected with respective binding posts, the outer ends of the contact rods projecting slightly beyond the second body member, and the outer ends of the contact plates having hollows for reception of respective contact rods.

JOHN WERITZ.
